Primary Examiner — Andrew Kerr*Assistant Examiner* — Chariton Alexakis*(74) Attorney, Agent, or Firm* — Armstrong Teasdale LLP(57) **CLAIM**

The ornamental design for a grooved container, as shown and described.

DESCRIPTION

FIG. 1 is a perspective view of a grooved container, showing our new design;

FIG. 2 is a side elevation view thereof;

FIG. 3 is the opposite side elevation view of FIG. 2;

FIG. 4 is a top plan view thereof; and,

FIG. 5 is a bottom plan view thereof.

The broken lines in the drawings depict portions of the grooved container that form no part of the claimed design.

1 Claim, 4 Drawing Sheets# US D982,445 S
